RAY P. JACKSON, OF EDGEWOOD PARK, AND WILLIAM SCHAAKE, OF PITTSBURGH, PENNSYLVANIA, ASSIGNEES TO WESTINGHOUSE ELECTRIC AND MANUFACTURING COMPANY, A CORPORATION OF PENNSYLVANIA.

SUSPENSION DEVICE FOR INSULATORS.

1,248,498.

Specification of Letters Patent.

Patented Dec. 4, 1917.

Application filed December 4, 1915. Serial No. 65,025.

To all whom it may concern:

Be it known that we, RAY P. JACKSON, a citizen of the United States, and a resident of Edgewood Park, in the county of Allegheny and State of Pennsylvania, and WILLIAM SCHAAKE, a citizen of the United States, and a resident of Pittsburgh, in the county of Allegheny and State of Pennsylvania, have invented a new and useful Improvement in Suspension Devices for Insulators, of which the following is a specification.

Our invention relates to suspension devices and particularly to suspension devices for connecting insulating units that are used in high-potential electric systems.

One object of our invention is to provide a device of the above-indicated class the members of which shall be readily separable without the use of tools but which shall be positively locked against unintentional disengagement.

Another object of our invention is to provide means for connecting insulating units which shall permit of considerable relative movement of the insulator parts without the disengagement thereof.

Heretofore, devices of this character have been proposed but my invention provides a new and useful improvement therein that will more effectively accomplish the above-recited results.

Figure 1 of the accompanying drawing is a side view, partially in elevation and partially in section taken substantially on the line I—I of Fig. 2, of a series of insulating units suspended by devices embodying our invention. Fig. 2 is an end elevational view of the connecting means shown in Fig. 1; Fig. 3 is an end view, partially in section and partially in elevation, of the device shown in Fig. 2; Fig. 4 is a side elevational view of a connection such as we propose, in the process of being assembled; and Fig. 5 is a side elevational view of a rod member and its associated connecting pin.

The insulator shown in the drawing comprises a plurality of insulating units 1 and 2 that are suspended from one another by a plurality of suspension devices 3 and 4. Each of the insulating units 1 and 2 is provided with an upwardly-extending, frustoconical portion 5 having external corrugations 6, and with a recess 7 having internal

corrugations 8. Each of the connecting devices 3 and 4 is provided with an interiorly-corrugated cap member 9 that is disposed around the upwardly-projecting portion 5 of an insulator and is secured thereto by cement 10 or any other suitable material. Each connecting device is provided also with a rod member 11, the upper end of which is secured within the recess 7 by means of a suitable cementing material 12. The upper end of the rod 11 is provided with a plurality of oppositely and outwardly projecting portions 14 that are arranged in pairs, and each pair is positioned at right angles to the succeeding pair in order to more firmly engage the cementing material 12.

The cap member 9 is provided also with two internally-recessed upright portions 18 and 19. The recesses 20 and 21 therein are of substantially rectangular shape (as illustrated in Fig. 1 and Fig. 4) and are severally provided with a transverse groove 22. The outside wall of each of the recessed portions 20 and 21 is provided with a rectangular aperture 23.

Referring particularly to Fig. 5, the lower end of the rod member 11 is provided with a widened and flattened portion 24 having a modified sector-shaped aperture 25 cut therethrough. A pin member 26, of approximately pear-shape in cross-section, is provided to interlock the rod member 11 with the cap member 9.

A suspension member, such as we have herein described, may be assembled by placing the rod member 11 in the opening 27 between the upright members 18 and 19 and inserting the pin member 26 in a manner to be described. When the members 9 and 11 occupy the relative positions shown in Fig. 4, the apertures 23 of the upright members sufficiently register with the aperture 25 of the rod member to permit of the insertion of the pin member 26 if the peaked portion thereof is biased to one side of the vertical position, as shown by the solid lines 26, in Fig. 4. After the pin 26 has been inserted, the peaked portion thereof is turned to a vertical position as shown by the dotted lines 26' in Fig. 4 and is caused to engage the groove 22 by the application of a tensile force.

The members 9 and 11 may be intention-

ally separated by forcing said members together as shown in Fig. 4 and by turning the pin 26 until the peaked portion thereof is biased to one side of the vertical position, 5 when the pin 26 may be laterally withdrawn.

It will be readily seen that the peaked portion of the pin 26 is normally caused to assume a vertical position because of its co-operation with the groove 22 and is secured, therefor, against unintentional dislodgment. It will also be seen that this connection permits of considerable relative movement of the connecting parts when they are 10 in a locked relation. This feature is highly desirable for suspension devices of the class under consideration, as those skilled in the art will readily understand.

We do not wish to be restricted to the 20 specific structural details herein set forth since various modifications thereof may be effected without departing from the spirit and scope of our invention and we desire, therefore, that only such limitations shall be 25 imposed as are indicated in the appended claims.

We claim as our invention:

1. A suspension device comprising a cap member having spaced upright portions that 30 are provided with lateral perforations and transverse recesses, a rod member having a perforated blade-like portion that is adapted to be received between the said upright portions, and a pin of modified cylindrical form 35 that is shaped to be received in said transverse recesses only after having been completely projected through the lateral perforations in said upright portions.

2. A suspension device comprising a pin 40 member of modified cylindrical form that is provided with a laterally projecting portion, a cap member having two upright members that are provided with lateral perforations and recessed to receive the pro-

jecting portion of the pin member only 45 when it is completely extended through said perforations and while the suspension device is in an operative position, and a rod member one end of which is flattened and broadened and has an aperture formed there- 50 in through which said pin member is projected.

3. A suspension device comprising a cap member having two upright portions provided with perforations and two laterally 55 extending portions that are transversely recessed, a rod member having a perforated blade-like portion that is adapted to be received between said laterally extending portions, and a pin member of modified cylindrical form that is adapted to separably 60 connect said cap to said rod member, said pin being inserted or withdrawn only when the perforations in said upright members register with the perforation in said rod 65 member and engaging the transversely recessed portions only when completely projected through the perforations in said upright portions.

4. The combination with a plurality of 70 suspended insulator units of a connecting means comprising a rod member having a perforated blade-like portion, a cap member having a plurality of recessed upright portions, the tops of said recesses respectively 75 having a transverse groove therein, and a pin member that is adapted to separably lock said rod member to said cap member and has a projecting portion that is adapted to engage the groove in said recessed portion and to be maintained in a given position during normal operation of said connecting means.

In testimony whereof, we have hereunto subscribed our names this 30th day of Nov., 1915.

RAY P. JACKSON.
WILLIAM SCHAAKE.
